DOOR LOCKING MECHANISM

Arthur F. Pruner, Oklahoma City, Okla.

Application March 7, 1936, Serial No. 67,600

13 Claims. (Cl. 292—172)

My invention relates to locking mechanisms for automobile doors and the like and more particularly to such mechanisms which lock by a change in position of the outside knob or handle, and without the use of a key.

Locking mechanisms in use today have several disadvantages. They make it necessary for the operator to use a key to lock his car from the outside; the car handle protrudes from the side 10 of the car allowing a hand hold for hi-jackers; it is necessary to lock all save one of the car doors from the inside and many times this is overlooked, necessitating re-opening of the doors; and the protrusion of the handles from the sides of 15 the car add wind resistance and detract from the desired streamline effect.

It is the purpose of my invention to overcome all of the above mentioned disadvantages, making it unnecessary to lock any of the doors from the 20 inside, or to use a key to lock the doors from the outside. My mechanism is so constructed that the outside door handles of all doors recede into an inaccessible position inside the door when the car is locked, the outer surface of the handle being flush with the exterior surface of the door, allowing no hand hold for hi-jackers and greatly 25 adding to the streamline design of the car.

I consider the device new, novel, practical, and of utility.

With these and other objects in view as will 30 more fully appear hereinbelow, my invention consists in the construction, novel features, and combination of parts hereinafter more fully described, pointed out in the claims hereto appended, and illustrated in the accompanying three-sheet drawing, of which,

Figure 1 is a fragmentary perspective view of 35 a car door with my device installed showing the normal position of the outside door handle when the door is not locked;

Figure 2 is a view similar to Fig. 1 showing the 40 relative position of the handle when the car door is locked;

Figure 3 is a perspective view of a portion of a 45 car door taken from the inside of the car, showing the normal position of the inside door handle and its range of movement for opening or locking the door from the inside;

Figure 4 is a perspective view of a part of the 50 mechanism which locks the outer door handle inside its recess in the door;

Figure 5 is a perspective view of a portion of the 55 mechanism which co-operates with the outer door handle to unbolt or to lock the door from the outside;

Figure 6 is a side elevation of the part of the mechanism shown in Fig. 4;

Figure 7 is a plan elevation of the portions of the mechanism shown in Figs. 4 and 5;

Figure 8 is a perspective view of the latch assembly with the power transmitting tube in operative relation thereto;

Figure 9 is a side elevation of the latch assembly with the small plate and power transmitting tube removed; and,

Figure 10 is a plan elevation of the latch assembly and power transmitting tube taken from the bottom looking upward.

For ease in description the mechanism shown in all figures except Figures 1 and 3 is applicable to a right hand car door which opens at its forward edge, or to a left hand car door which opens at its rear edge.

Like characters of reference designate like parts in all the figures.

It is understood that various changes in the form, proportion, size, shape, weight, material and other details of construction, within the scope of my invention may be resorted to without departing from the spirit or broad principle of my invention and without sacrificing any of the advantages thereof; and it is also understood that the drawings are to be interpreted as being illustrative and not restrictive.

The inventive idea involved is capable of receiving a variety of mechanical expressions one of which, for the purpose of illustrating the invention, is shown in the accompanying drawings wherein:

Referring more particularly to Figs. 4, 5, 6, and 7, numeral 1 designates an outer plate having a perforation 2 in each of its corners, and adapted to be thereby secured in spaced relation to the outer wall of a substantially hollow door. A door handle crank 3 is rotatably mounted on the outer surface of the plate 1 and is slidably vertically adjacent thereto, its upper end being journaled in a lug 4 stamped out of the plate 1, and its lower end being journaled in a journal box 5. This box 5 slides in a slot 6 in the plate 1. The edges of slot 6 fit in lengthwise guide grooves in the box 5, one portion of the box being on the outer surface of the plate 1, as shown in Fig. 5, and another portion of the box on the inner surface of the plate 1, as in Fig. 4. A horizontal slot 7 is provided in the box 5 to allow movement of a pin 8 carried by the crank 3. The pin 8 hitting the sides of the slot 7 limits the rotation of the crank 3 in either direction. The offset portion 9 of the crank 3 is held normally 50

adjacent the plate 1 by a coiled spring 10, one end of which bears on a pin 11 carried by the box 5 and the other end of which fits through a perforation in the lower end of the crank 3.

5 A bolt trigger 12 is slidably mounted on the plate 1 through a slot 13 in the plate, and is adapted to be moved by the offset portion 9 of the crank 3 as it rotates. A slide plate 14 (Fig. 4) located on the opposite side of the plate 1 is riveted securely to the trigger 12 and slides through a slot 15 in a bracket 16 riveted on the inner surface of the plate 1. One end of a locking link 17 (Figs. 4 and 6) is pivotally mounted on the plate 1 by a bushing rivet 18. Its other end pivotally connects to one end of a connector link 19 whose other end is pivotally mounted on the box 5 by a bushing screw 20. The link 17 carries a lug 21, to which one end of a spring 22 is attached, the other end of the spring being anchored to a lug 23 made integral with the bracket 16. One end of a lock member 24 is pivotally mounted on the inner surface of the plate 1 and its movement in either direction is controlled by an ordinary tumbler lock mechanism (not shown). The member 24 normally remains in the position shown in Figs. 4 and 6. Its outer edge contacts a lug 25 integral with the bracket 16, and this lug prevents its rotation in one direction. It can only be rotated partially in the opposite direction by insertion of a key (not shown) in the tumbler lock. When being rotated in this direction by a turn of the key its outer end contacts either link 17 or link 19.

A door handle 26 (Figs. 1 and 2) is adapted to be attached to the upper end of crank 3, which extends upward through a handle recess 27 in the door. It will be seen, from the description thus far, that if the door handle 26 while in its operative position as shown in Fig. 1 is pushed downward into its recess, the crank 3 in sliding downward with the handle 26 moves the journal box 5 downward in its slot 6, and the links 17 and 19 move from their position shown in Fig. 4 to a vertically aligned position shown in Fig. 6 by the center line X—X (Fig. 6). When the links 17 and 19 reach this point the spring 22 pulls them into the position shown in Fig. 6, at which point their movement is limited by contact with the lock member 24, which in turn is prevented from movement both by the tumbler lock mechanism and by the lug 25. The links 17 and 19 are held in this position by the spring 22 and a spring 28, one end of which bears upward on the bottom of the journal box 5. With the links 17 and 19 held in this position it will be seen that the upper surface of the handle 26 would be flush with the surface of the door (as in Fig. 2), and this being the only exterior handle on the door, it would not be possible to open the door from the outside. A key, however, may be inserted in the tumbler lock (the key entrance only being shown in Fig. 1) and by turning the key clockwise, the outer end of the lock member 24 forces the links 17 and 19 against the tension of the springs 22 and 28 from their position shown in Fig. 6 to a position past the center line X—X, at which time the spring 28 by its upward thrust on the box 5 forces them outward to the position shown in Fig. 4. At the same time, of course, the crank 3 slides upward raising the door handle 26 out of the recess 27 into operation position. Thus the handle 26 is free to turn and open the door. It will be noted that the outward movement of the links 17 and 19 and the upward movement of the crank 3 is limited by a lug 29

carried by the plate 14. The purpose of its corresponding lug 30 will be hereinafter explained, as will the action of the handle 26 on the door bolt.

Having explained the construction of the outer plate locking mechanism I will now explain the inner door plate mechanism and its relation to the inside door handle. Please bear in mind that the outer door plate mechanism and the outside handle may be located at any desired position 10 on the door.

Referring more particularly to Figs. 8, 9 and 10, the inner mechanism includes a latch plate 31 having through perforations 32 to facilitate its attachment to the inner edge of a door. Its flanged end 33 has a suitable aperture to allow the end of a door bolt 34 to slide therethrough and to be guided by the sides thereof and by a lug 35 integral with the flanged end 33. The sliding movement of the bolt 34 is also guided by inwardly projecting spacer lugs 36, 37 and 38 integral with the plate 31. The ends of these lugs fit in suitably located slots in an inner housing plate 39 (Fig. 8), and their longitudinally extending shoulders serve not only as bolt guides 25 but also to space the two plates 31 and 39 apart. The plates are held in this spaced relation by screws 40.

The bolt 34 has a downwardly projecting end 41 which contacts the lug 37 to limit the outward movement of the bolt. One end of a spring 42 bears against the inner end 41 of the bolt, normally holding it at its limit of outward movement. A geared bolt bar 43 has its lower edge slidably supported and guided by the lugs 37 and 38. Its upper edge supports and guides the lower edge of the bolt 34. This relation is maintained and sideplay is prevented by the proper spacing of the plates 31 and 39, and by the proper spacing of lugs 36, 37 and 38. It will be seen that one end of the bar 43 is adjacent the end 41 of the bolt 34 and that forced movement of the bolt bar 43 would cause the bolt 34 to move against the spring 42 releasing the opposite end of the bolt from its corresponding seat, thus allowing 45 the door to be opened freely.

Movement of the bolt is accomplished by a toothed gear 44 rotatably mounted between the lugs 31 and 38 and journaled between the plates 31 and 39. One irregular shaped end of a door handle pin 45 fits a similar shaped central perforation in the gear 44 and is rigidly secured to the gear. The pin 45 extends through the plate 31 and carries the inner door handle 46 on its opposite end. The teeth on the bar 43 do not mesh with the teeth of the gear 44 when the gear is in its normal position as shown in Fig. 9. The gear 44 is normally held in this position by a ball 47 seating in a V-shaped recess in the edge of the gear 44 opposite the teeth on the gear. This ball 47 is held in alignment with the lower edge of the gear by guides 48 and 49 formed in the lower edges of the plates 31 and 39 respectively, and is held in contact with the edge of the gear by a spring 50, one end of which bears directly on the ball 47. Turning the inside door handle in either direction unseats the ball from the V-shaped notch in the gear 44 against the tension of the spring 50. When the rotation stops and the handle again approaches its normal position the ball 47 and the spring 50 cause the handle to stop at its normal position and the gear 44 likewise. When the gear 44 is rotated clockwise (considering Fig. 9 only) the teeth on the gear contact the bar 43 and move it toward the 75

outer edge of the door. The bolt 34, being limited against movement in this direction, remains stationary, the bar 43 simply sliding along the lower edge of the bolt. When the gear 44 is rotated in the opposite direction, its teeth contact the bar 43 and move it against the end 41 of the bolt thus moving the bolt, and unlatching the door.

Having explained both the relation of the inner door handle to the inner plate mechanism and the relation of the outer door handle to the outer door mechanism, I will now explain the relation of the inner door handle to the outer door mechanism, and the relation of the outer door handle to the inner door mechanism.

It will be remembered that the glass in an ordinary door comes between these two mechanisms and that the power must be transferred around the edge of the glass. To do this I prefer to use a substantially U-shaped hollow tube 51 housing a plurality of ball bearings 52 (Fig. 10). The straight sides of the tube act as sleeves for cylindrical rods 53 and 54 which may slide longitudinally therein. Longitudinal inward pressure applied on one of the rods is transmitted from its inner end to each of the ball bearings in turn, and reaches the inner end of the other rod, moving it in an outward direction. There is practically no power lost in transmitting the power from one rod to the other.

The outer end of the rod 54 is fitted with a suitable connection 55 (Figs. 8 and 10), a perforation in which receives an inwardly projecting cylindrical arm 56 carried by one end of the bar 43. The outer end of the other rod 53 bears directly against the flanged end of the plate 14 (clearly shown in Fig. 7). One end of the U-shaped tube 51 is threaded and is rigidly secured to the bracket 16 on the inside surface of the outer door plate 1, by nuts 57 and 58 as shown in Figs. 4, 6 and 7. The opposite end of the tube is secured in a similar manner to an inwardly extending lug 59 (Figs. 8 and 10) integral with the plate 39. The arm 56 passes through a longitudinal slot 60 in the plate 39 and is free to slide backward and forward in the slot as the bar 43 moves. The curved portion of the tube 51 may be rigidly secured in any desired manner to the door frame. Also the straight sides of the tube may be varied in length so that the inner and outer door mechanisms may be placed at varying distances from the edge of the door. The curved portion of the tube 51 may also be varied in shape in order to avoid any obstacles.

As previously mentioned the bolt 34 is held in its normal locking position by the spring 42, and the end 41 of the bolt bearing against the end of bar 43 also holds the bar in its normal position (Fig. 9). The arm 56 carried by the bar 43 pushes the rod 54 into its normal position and the inward travel of the rod 54 is limited by the other rod 53 bearing against the end of plate 14 (Fig. 7). There is practically no play between the inner ends of the two rods and the bearings 52. A spring 61 (Fig. 6) mounted on the inner surface of plate 1 bears against the flanged end of plate 14 which in turn bears against the end of rod 53 and eliminates play between the ends of the two rods.

In operation when the bar 43 moves away from the door edge by manual counterclockwise rotation of the inner handle 46 and gear 44, as previously explained, the rod 54 follows the bar 43 because of the pressure of spring 61 on the end 75 of the other rod 53. In case the door has pre-

viously been locked from the outside and the handle is flush with the door sill, as in Fig. 2, at the time of this rotation the link 17 is contacted by the lug 30 carried by the plates 14 and is moved from its locked position in Fig. 6 past the center line X—X, at which point springs 28 and 61 move it to the position shown in Fig. 4. This movement allows the outside handle 26 to emerge from its recess into operative position, as in Fig. 1.

If the handle 26 is now rotated into the position shown by the dotted lines in Fig. 1 the portion 9 of the crank 3 contacts the adjacent edge of the trigger 12 forcing it to slide in its slot, and at the same time forcing plate 14 to slide and move the end of rod 53 inward. Rod 54 is thereby moved outward forcing bar 43 to move the bolt 34 inward against the tension of spring 42, thus unlatching the door. When the handle is released by the operator, spring 42 returns bolt 34, bar 43, and rods 54 and 53 to their normal positions. Spring 10 returns the outer handle 26 to its normal position.

It will also be seen that when the inside handle 46 rotates the gear 44 in a clockwise direction (Fig. 9), the bolt 43 slides toward the outer edge of the door, moves rod 54 with it, which in turn causes rod 53 to move plate 14, and as plate 14 moves, its integral lug 29 contacts the link 17, as in Fig. 4, and pushes the links 17 and 19 toward their position in Fig. 6, at the same time moving box 5 and crank 3 downward, which in turn causes the outer door handle 26 to seat in the recess 27, locking the door because of the inaccessibility of the handle.

It is obvious that the entire mechanism as shown in the drawings may be built reversed for application to doors which open in the opposite direction.

Obviously, the invention is susceptible of embodiment in forms other than that which is illustrated in the accompanying drawings and described herein, and applicable for uses and purposes other than as detailed, and I therefore consider as my own all such modifications and adaptations and other uses of the form of the device herein described as fairly fall within the scope of my invention.

Having thus described my invention, what is claimed and desired to be secured by Letters Patent is:

1. In a motor vehicle door provided with a window opening and a window pane vertically slideable in the door and the opening; a door bolt secured within the door on the inside of the glass, and operable by an inside door handle; an outside door handle adapted to recede into a pocket in the outer window ledge of the door; a handle retaining mechanism secured within the door on the outside of the pane, and operable by the outside receding door handle and by the inside door handle; and mechanical means passing around the edge of the glass for operably connecting the inside door handle and the outside handle locking mechanism whereby the inside door handle may initiate movement of said outer door handle toward or away from its seated position, and the outside door handle may operate to unlatch said door bolt.

2. In a device of the class described: an inside door handle; an outside door handle; a handle shaft for each handle; a slideable door bolt; a pinion on the inside handle shaft; and a toothed bar adapted to be moved in either direction by the rotation of said pinion, and adapted to move

- said door bolt when the bar moves in one direction, and to initiate movement of said outer door handle into an inaccessible position between the door walls when said bar moves in the opposite 5 direction.
3. In a door locking device; an outside door handle adapted to recede into a recess in the outer window ledge of a door; co-operating mechanical means adapted to retain said handle in 10 its receded position flush with the exterior of the ledge; cooperating key controlled means for releasing said retaining means and for initiating the return movement of said handle to its normal operative position; a door bolt; an inside door 15 handle; operative connections between said first-mentioned door handle and said door bolt; and operative connections between said first mentioned handle and said handle retaining mechanism.
- 20 4. In an automotive vehicle door, including inner and outer side walls and a glass panel slidably mounted therebetween; a door bolt operable by an inner door handle; a receding outer door handle adapted to recede into an inaccessible position 25 between the door walls; mechanism including a ball filled tube passing around the edge of the panel operably connecting the outer door handle with the door bolt; and mechanism adjacent the outer wall for locking the outer door 30 handle in its receded position; said first mentioned mechanism also operably connecting the outer and inner door handles around the edge of said glass, whereby movement is transmitted from said inner door handle to said outer handle 35 locking mechanism.
5. In a motor vehicle door provided with a window opening and a window pane vertically slidable in the door and the opening; a slidable door bolt secured within the door on one side 40 of the glass and operable by an inside door handle; an outside door handle adapted to recede into an inaccessible seat between the walls of the door and operably connected to said door bolt; a handle retaining mechanism within the 45 door on the other side of the glass adapted to retain said outer door handle in a receded position; operative connections between said inner door handle, said handle retaining mechanism, and said outer door handle whereby said inner 50 door handle initiates movement of said outer door handle into or out of its receded position; spring means for causing said handle to move into a receded position after the initial movement in that direction; and spring means for completing the 55 movement of said outer door handle from its receded position into an accessible position after such movement has been initiated.
6. In a door having a vertically slidable panel 60 therein, a door bolt at one side of the path of a panel operable by a handle on the same side of the path of the panel; an operating handle on the opposite side of the path of the panel adapted to recede into an inaccessible position between the walls of said door; mechanism for retaining 65 said door handle in its receded position; an enclosed ball bearing raceway adapted to transmit positive movement from said first mentioned door handle to said receding door handle, and from said receding door handle to said door bolt, where- 70 by movement of the receding door handle into or out of its receded position is initiated by movement of said inner door handle; and spring means for completing the movement of said outer door handle after said movement in either direction 75 has been initiated.
7. In an automobile door having a vertically 5 slidable panel therein, a door bolt at one side of the path of the panel, and a bolt operating door handle on the same side of the path of the panel; a bolt operating door handle on the opposite side of the path of the panel adapted to recede into an inaccessible position between the outer and inner walls of said door; a pinion mounted adjacent and adapted to rotate with one of said handles; a toothed bar adapted to be slidably moved in either direction by the rotation of said pinion; a tubular ball bearing raceway having one of its ends operably connected to said toothed bar and having its other end extending around an edge of the panel; and mechanism within the door 10 adjacent the receding handle for forcing said handle into its receded position and for retaining it in that position, and operably connected to the other end of said tubular ball bearing raceway; said toothed bar, when moved in one direction 15 by said pinion, adapted to retract said door bolt, and when moved in the opposite direction adapted to transmit movement through said ball bearing raceway to said receding door handle.
8. In a door having a vertically slidable glass 20 panel therein, and a door bolt located on the inside of said panel and operable by an inside handle; an outer door handle adapted to recede into a recess in the door on the outside of said panel; a link mechanism operable by said outer 25 door handle and by said inner door handle, and adapted to retain said outer door handle in a receded position; and mechanical means operably connected at one end to said link mechanism and passing from said link mechanism around an 30 edge of said panel to said inner door handle and having its other end operably connected to said inner door handle and said door bolt.
9. In a motor vehicle door provided with a window opening and a window pane slidably vertically in the door and the opening, with a slide- 35 able door bolt on the inside of the pane operable by an inner door handle; an outer door handle adapted to recede into a pocket between the walls of the door; link mechanism operably connected to the inner and outer door handles, and adapted 40 to retain the outer door handle in a receded position; and operative connections between the outer handle and the door bolt and between the inner door handle and the link mechanism.
10. In a door provided with a window opening, with a window pane vertically slidable in the door and opening, and with a slideable door bolt on the inside of the pane operable by an inner door handle; mechanism including a pinion en- 45 gaged slideable toothed bar constituting an operable connection between the bolt and the inner door handle; an outer door handle adapted to recede into an inaccessible position in a pocket between the walls of the door; mechanical means outside the path of the panel responsive to movement of the inner handle for initiating movement of the outer handle into or out of its receded position, said mechanical means including parts which are responsive to movement of the outer 55 handle for retaining said outer door handle in a receded position; and mechanism including a ball filled tubular element connected to the toothed bar and to the retaining mechanism and passing around the path of the panel for transmitting 60 movement from said inner handle to said retaining mechanism.
11. In a device of the class described, an inside door handle; an outside door handle adapted to recede into a pocket between the door walls; a 65

shaft for each handle; a slidable door bolt; a pinion on the inside handle shaft; a toothed bar operably engaged by the pinion and adapted to operably engage the door bolt while moving in one direction; mechanism including a ball filled tube constituting an operable connection between said toothed bar and said outer handle; and mechanism adjacent the outer handle adapted to retain said handle in its receded position, said mechanism including a pair of link members pivotally connected to each other at one end, the opposite end of one link being pivoted to a stationary plate, and the opposite end of the other link pivotally connected to the outside handle shaft.

12. In a door having a panel slidable vertically therein, a door bolt on one side of the path of the panel; a receding door handle on the opposite side of the path of the panel adapted to be secured in an inaccessible position in a pocket between the door walls; and an operative connection, comprising a ball filled tube, passing from the door handle around the panel to said door bolt, and operably connected to each, whereby a rotary motion of said door handle is converted into a

push movement and transmitted through said balls to said door bolt.

13. In a door having a slidable door bolt operable by an inside door handle, and a panel slidable vertically in said door, an outside handle adapted to recede into a pocket between the walls of the door; means for initiating movement of said handle into its receded position and for retaining said handle in its receded position; spring means for completing the movement of said handle into its receded position after said initial movement; and operative connections between said inner door handle and said retaining mechanism comprising a toothed bar slidable by the rotation of a pinion attached to said inner door handle, and a ball filled tube passing from said toothed bar around the path of the panel to said retaining mechanism; said ball filled tube also adapted to transmit movement from said outer door handle to said toothed bar; and said toothed bar adapted to move said door bolt when said bar moves in one direction, and to move said retaining mechanism when said bar moves in the other direction.

ARTHUR F. PRUNER. 25
